WINDOW MOUNTING**Irwin R. Lance and Irwin R. Lance II, O'Hara Township, Allegheny County, Pa.**

Application October 21, 1953, Serial No. 387,426

9 Claims. (Cl. 20—52.2)

This invention relates to a window mounting and more particularly to improved means for readily inserting and removing a window or sash with respect to its frame.

The conventional double-hung windows in use today require an assortment of auxiliary equipment such as pulleys, cords, sash weights, balancing springs, and the like. Additionally, such window constructions are subject to many disadvantages. For example, the windows very easily rattle as from gusts of wind or conversely become so stuck that it is difficult to open or close them. Further, weather stripping must often be used to keep out rain, drafts of air, and the like. In particular, washing the outside of such windows is not only inconvenient but also hazardous, especially in the case of high buildings.

The present invention eliminates all of these objections. A window or sash mounted in accordance with this invention requires no weather stripping and very few auxiliary parts. Further, the window may be quickly and easily removed as for cleaning and then replaced, and in spite of such ease of mounting, the window is rattleproof and thickproof.

In one form the present invention includes a compressible strip for mounting a window sash in its frame. The strip is folded longitudinally to impart the compressibility and has spaced-apart pockets or openings. The strip is inserted at the folded edge between the sash and its frame to make resilient contact therewith. Pins carried by the frame make a snap engagement with the pockets when the insertion of the strip reaches a predetermined point to hold the parts in assembly. To remove the strip and therefore also the sash, the folds of the strip are brought together to clear the pin and then withdrawn. In the preferred form, the mounting strip has an enlarged edge which forms a separating rib to space apart upper and lower sashes.

The accompanying drawing illustrates a presently preferred embodiment wherein:

Figure 1 is a front elevation of a double-hung window embodying the instant window mounting;

Figures 2 and 3 are sections of Figure 1 on the lines II—II and III—III, respectively;

Figures 4 and 5 are perspective views of a side and top strip, respectively, used in the window mounting; and

Figure 6 is a fragmentary sectional view similar to Figure 2 of a conventional double-hung window.

Referring to the drawing, a double-hung window generally shown at 10 includes an upper and lower window or sash 11 and 12, respectively, in which glass panes 13 are conventionally carried. A frame 14 has side jambs for mounting sashes. The frame encloses the sashes and has a strip 15 fixed at the top and strips 16 and 17 fixed at the sides. The upper sash 11 is resiliently held against the strips 15, 16 and 17 by longitudinal mounting strips or fittings 18 and 19 which extend down the sides of the frame 14. Each mounting strip is preferably metallic and includes a somewhat rectangular edge or guide portion; one (outer) side of the fitting member is

2

extended and folded back on itself to form a resilient wedge or spring plate portion 21. Pins 22 carried by the frame 14 engage indented pockets or openings 23 which are spaced longitudinally along the mounting strip to hold the parts in assembly. A separating strip 24 is shown secured to the top of the frame 14 and spaced from the strip 15 to receive the upper sash 11 therebetween.

Transversely-extending outer side panel portions 26 are positioned for substantially flush mounting against the jamb portions of the frame 14. One end of each base or side panel portion is, as shown in Figure 2, connected by a spring-like or resilient connection to the transversely-extending inner spring plate portion 21 to thus provide a rail for the operative movement of the sash 11 or 12. The spring portion 21 extends transversely from its connection to 26 in an inwardly-diverging relationship that defines a substantially V-shaped section therewith.

The guide portion 20 projects inwardly from the panel portion 26 at an angle thereto and, with the diverging end of the spring plate 19, defines a somewhat box-like section for guiding the side of the sash in its operative movement. More specifically, this box-like section, as shown in Figure 2, is in guiding engagement with the adjacent corner portions of the sash. Since the sides of the sash 11 and 12 are sloped or inclined inwardly in a somewhat complementary manner with respect to the plates 21 which tightly abut thereagainst, it is apparent that a resilient-wedging type of action is employed to hold each sash in its operative position within the frame 14.

It is a simple matter to remove either or both of the sashes 11 and 12 by outwardly forcing or compressing the plate portions 19 against the resiliency of their mountings. That is, the spring plate portion 19, as biased to resiliently abut the sash, not only holds the sash in an operative position without rattling and weather-strips the installation, etc., but also makes possible a simple procedure for installing and removing the installation from between jam portions of a conventional frame 14.

The lower sash 12 bears against the rectangular edges of the mounting strips 18 and 19 and is itself held in position by mounting strips 18a and 19a which extend up the sides of the frame 14 and are similar in construction to the mounting strips 18 and 19. Pins 22a hold the strips 18a and 19a in position in a manner like that of pins 22. If desired, a second separating strip 25 may be secured to the top of the frame 14 and spaced from the strip 24 to receive the lower sash therebetween as when it is in a raised position.

To assemble the present window construction, the upper sash 11 is first placed between strips 15 and 24 and held against the strips 15, 16, and 17 while the resilient wedge 21 of either strip 18 or 19 is inserted between the sash and the frame until a pin 22 reaches a pocket 23. If desired, the pins 22 may be spring-loaded to facilitate this operation. Also, the pins may be carried by the sashes, and the openings 23 may be in the frame. Due to the compression of the resilient folds of the mounting strip as a result of the insertion, the pin is quickly forced into the pocket and the side 26 of the strip is quickly flattened against the frame 14. Here and in the claims such a fitting is referred to as a snap engagement or snap holding engagement and is meant to indicate a quick engagement of the designated parts and subsequent quick disengagement as hereinafter mentioned. The second molding strip for the upper sash 11 is next similarly installed. The lower sash 12 is now held against the rectangular edges 20 while strips 18a and 19a are inserted in a like manner between the lower sash and the frame until the pins 22a snap into the pockets or openings 23 of those strips. The compression of the folds of each strip is not sufficiently great to prevent raising and lowering of the sashes.

To disassemble the present window construction, the folds of one of the mounting strips cooperating with the lower sash are brought together to clear a pin 22a and then withdrawn from the assembly. This is readily accomplished by pushing against the rectangular edge 20a of the strips 18a or 19a substantially in the direction indicated by the arrow 27. Thereafter, the order given in describing the assembly of the window construction is followed in reverse. However, it is also possible to remove the sashes after only one of the mounting strips is withdrawn, and ordinarily this procedure is followed when the sashes are to be immediately replaced as after cleaning them.

It is emphasized that the rectangular edges on the mounting strips bear against the sides of the sashes and prevent them from moving forwardly out of the frame. Also, the rectangular edges 20 serve as a separating rib and space apart the sashes 11 and 12. Further, the rectangular edges 20a and the separating strip 25 form attractive trim work around the inside of the window. This construction thereby eliminates standard strips like strips 28 and 29 secured to a frame 30, as shown in the conventional double-hung window of Figure 6, which the sashes 31 and 32 loosely contact in order to allow raising and lowering of those sashes. The present window mounting, in contrast, eliminates any opportunity for rattling and the need for weatherproofing by means of the resilient strips. Indeed, the strips themselves afford a weatherproofing action. Additionally, also because of the resilient nature of the mounting strips 18 and 19 against which the sides of the sashes slide, the sashes do not stick. Further, the sashes are easily removed for safely washing the panes 13 within the room in which they are used and then quickly replaced as described.

If desired, the strips 18a and 19a may be solid, that is, free of the openings 23. In this case, in order to retain such a strip, the pin 22a may be driven into the frame to make a snap engagement against the side of the rectangular edge 20a which faces the room after the strip 18a or 19a has been inserted that far.

While the foregoing disclosure describes a presently preferred embodiment, it is understood that the invention may be practiced in other forms within the scope of the following claims.

We claim:

1. A fitting construction for operatively mounting a sash in a frame which comprises, a longitudinal member having a transversely-extending outer side panel portion for substantially flush mounting against a jamb portion of the frame, said member having a transversely-extending inner spring plate portion to provide a surface for operative movement of the sash thereon, said spring plate portion being resiliently connected to one transverse end of said side panel portion and extending transversely therewith in an inwardly-diverging relation that defines a substantially V-shaped section therewith, said member also having a guide portion connected to an opposite end

of said panel portion and projecting inwardly therefrom at an angle thereto, and said spring plate portion having a diverging end positioned adjacent to said guide portion to define a somewhat box-like section therewith for guiding a side of the sash in its operative movement with respect to said spring plate portion.

2. A fitting as defined in claim 1 wherein said box-like section has surfaces in guiding engagement with a corner portion of the sash.

3. A fitting as defined in claim 1 wherein said member is of resilient strap-like metal.

4. A fitting as defined in claim 1 wherein retaining means engages said member and is secured to the jamb portion of the frame to hold said member in position on the jamb portion.

5. A fitting as defined in claim 1 wherein, the sash has a transversely-inclined outer side portion, and said spring plate portion has a resilient-wedging engagement with the outer side portion to hold the sash in an operative position within the frame.

6. A fitting as defined in claim 1 wherein said spring plate portion is biased to tightly-resiliently abut along an outer portion of the sash and to flex from its diverging end outwardly towards said panel portion for removing the sash out of an operative position with respect to the frame.

7. A fitting as defined in claim 1 wherein said longitudinal member is of one-piece metal construction and opposite longitudinal ends of said metal piece are in an adjacent relationship at said box-like section.

8. A fitting as defined in claim 1 wherein a pair of members of the defined construction are substantially flush-mounted against a pair of opposite jamb portions of the frame to cooperate with opposite sides of the sash in its operative movement.

9. A fitting as defined in claim 8 for operatively mounting an upper and a lower sash in a frame wherein, a second pair of said members of the defined construction is provided, the first of said pairs is positioned to operatively mount the upper sash in the frame, the second of said pairs is positioned in a transversely-spaced relation behind said one pair to operatively mount the lower sash in the frame, and said members of said second pair having the one transverse ends of their panel portions positioned adjacent to the box-like sections of said members of said first pair, so that the lower sash will be guided at its front and back side corners between the box-like sections of said members of said first and second pairs.
